(57) **CLAIM**

The ornamental design for a storage container with a securing belt for an automobile, as shown and described.

DESCRIPTION

FIG. 1 is a perspective view of a first embodiment of a storage container with a securing belt for an automobile; FIG. 2 is a perspective view of a second embodiment of the storage container with the securing belt; FIG. 3 is a perspective view of a third embodiment of the storage container with the securing belt; FIG. 4 is a bottom perspective view of the second embodiment of the storage container of FIG. 2, absent a base; FIG. 5 is a front view of the second embodiment of the storage container of FIG. 2; FIG. 6 is a rear view of the second embodiment of the storage container of FIG. 2; FIG. 7 is a top view of the first and second embodiments of the storage container of FIG. 1 and FIG. 2, respectively; FIG. 8 is a bottom view of the first and second embodiments of the storage container of FIG. 1 and FIG. 2, respectively; FIG. 9 is a right-side view of the first and second embodiments of the storage container of FIG. 1 and FIG. 2, respectively; FIG. 10 is a left-side view of the first and second embodiments of the storage container of FIG. 1 and FIG. 2, respectively; and, FIG. 11 is a perspective view of the securing belt without the storage container, with the securing belt shown separately for ease of illustration.

The broken lines represent environmental subject matter and represent unclaimed portions of the storage container. The broken lines form no part of the claimed design.
